UNITED STATES PATENT OFFICE.

THERON L. HILES, OF NILES, MICHIGAN.

APPARATUS FOR SUPPLYING FLUID IN VARYING VOLUMES.

Application filed July 30, 1923. Serial No. 652,760.

To all whom it may concern:

Be it known that I, THERON L. HILES, a citizen of the United States, residing at Niles, in the county of Berrien and State of Michigan, have invented a certain new and useful Apparatus for Supplying Fluid in Varying Volumes, of which the following is a specification.

The invention pertains to a means adapted to supply a fluid under pressure to a pipe line or service main, and to maintain the pressure in the service main substantially constant notwithstanding variations in the volume which may be consumed from time to time.

Generally stated, the object of my invention is to produce an apparatus of the character indicated, which is at the same time more efficient in operation and more economical in the consumption of power than other apparatus of the same general character heretofore produced.

In carrying out my invention, I employ, in combination, a compressor of a suitable or preferred type, and a governing means which is controlled by the pressure of the fluid under compression in the service main or pipe line and operates to coordinate the volume of fluid entering the compressor with that discharged therefrom into the service main. The combination of a compressor and governing means, broadly considered, has long been in common use in the industrial arts, but in all instances, so far as I am aware, prior apparatus employ a compressor which operates at substantially its maximum capacity at all times, there being associated with the compressor a by-pass, which, when the volume being consumed at any given time falls, serves to return from the compressor outlet to the inlet the excess, or unused portion of the fluid. Obviously such return of the excess, or unused portion of the fluid compressed results in a large reduction in the general efficiency of the apparatus, especially when as is usually the case, the system seldom operates at maximum capacity. Thus, not only is there a waste of power in compressing and recompressing the fluid, but such recompression of the fluid generates heat which must be provided for by special cooling equipment. Also, the return of unused portions of the fluid to the compressor inlet

renders it difficult to control properly the flow to the compressor of a plurality of fluids through separate inlets, as is the case when the apparatus is employed, for example, in mixing and compressing air and gas for combustion purposes, the result being that the desired proportion of the gases constituting the mixture is materially disturbed.

In my apparatus I have eliminated the necessity for using a by-pass in connection with the compressor, by the coordination of the volume of fluid entering the service line with that entering the compressor and passing therethrough. To this end I employ valve means, under the control of a governor in communication with the service line, which serves not only to control the flow of fluid through the compressor to the service main, but also to control any tendency of the fluid to flow in the reverse direction, that is to say, from the service main to the compressor; but since the control of the outlet port is coordinated with the control of the inlet port, the volume of fluid discharged by the compressor at any given time corresponds to that which is entering the compressor at that time. On the other hand, should the pressure in the service main suddenly rise due to a reduced demand, the ensuing restriction of the outlet port of the compressor, together with a restriction of the inlet port prevents or at least materially retards the transmission of the increased pressure from the service main to the compressor. As a result, the compressor is merely called upon to compress the limited volume of fluid admitted thereto, being unburdened of an excessive back-pressure, as well as of an unused portion of the fluid returned through a by-pass. As a further result, the tendency of the fluid in the service main to surge or pulsate as is commonly the case, especially when compressors of the centrifugal or non-positive type are employed, is substantially overcome. This result is particularly advantageous in cases where the apparatus is employed for compressing air and gas for combustion purposes because, as is well understood in the art, a fluctuating pressure in the service main of a gas supply system substantially reduces the efficiency of the gas combustion due to the fixed or non-

flexible character of the burners. Also, the aforesaid result is advantageous because it renders it practicable to use compressors of the non-positive type which are more economical in the use of power, and because in the absence of a fluctuating pressure in the service main, the formation of a combustible mixture, through the induction of air into the system at the burners, is rendered impossible.

For convenience, I have herein shown and will describe my invention as applying more particularly to gaseous fuel supply systems.

Figure 1 of the drawings is a view partially diagrammatic in character of a gaseous fuel supply system embodying an apparatus constructed in accordance with my invention. Fig. 2 is a vertical sectional view of a positive type compressor equipped with a controlling means constructed in accordance with my invention. Fig. 2^a illustrates a detail of construction. Fig. 3 is a similar view but showing a non-positive or fan type of compressor with a different form of valve means. Fig. 4 is a horizontal sectional view taken substantially in the line 4—4 of Fig. 3. Fig. 5 is a vertical sectional view taken in the plane of line 5—5 of Fig. 3.

Referring now to Fig. 1, the system comprises generally a reducing valve 7 interposed in a pipe line 8 communicating with a suitable source of fuel gas supply. 9 designates generally the compressor, and 10 the controlling means therefor embodying valve-controlled inlet passage for gas and air, and an outlet passage for the mixture, the pipe line 8 being connected to discharge into the gas inlet passage. 11 (Figs. 3 and 5) indicates a slide valve in the form of a flat plate constituting part of the mechanism for controlling the flow of the mixture through the compressor. This valve member 11 is mounted so that it is automatically controlled by the pressure in the outlet passage to coordinate with the volume of the mixture issuing from the compressor the combined volume of air and gas admitted to the compressor. 12 is a pipe line constituting the service main leading from the outlet of the compressor and having communicating therewith various branch or supply pipes provided with burners or unloading devices 13.

The reducing valve 7 may be of any preferred or well known construction. That shown herein comprises a casing 14 having a valve-controlled passage 15 therethrough. The valve in turn is controlled by a diaphragm 16 which is subjected to the pressure of the gas at the outlet side of the valve. This device is adjustable through the medium of weights 17 so as to maintain in the pipe line 8 at the inlet of the compressor a predetermined degree of pressure

of the gas. This pressure may, for example, be atmospheric.

The compressor 9 shown in Figs. 1, 3 and 4 is of the non-positive or centrifugal fan type, comprising an annular casing 18 having rotatively mounted therein an impeller 19, which is driven by means of an electric motor. This impeller is of the non-positive type but a blower of the positive type shown in Figs. 2 and 2^a may be employed. The inlet and outlet for the casing of the compressor, (Figs. 1 and 3) are herein arranged so as to be juxtaposed and hence capable of being controlled by a single valve member in the form of a flat plate. To this end the casing is shaped on opposite sides (Fig. 4) to provide suitable ways or channels 20 communicating with the casing at the axis of the impeller and each divided to form an air passage 21 and a passage 22 for fuel gas. Between said channels the casing has a radially extending portion 23 providing an outlet passage 24 terminating above the passage 22. The opposite channels 20 are brought together at their outer ends so that the pairs of passages 21 and 22 merge into single passages as at 20^a (Fig. 4). As will be understood, the arrangement is such that the valve means is adapted to restrict or enlarge simultaneously and to the same degree the effective areas of the inlet and outlet openings.

The controlling means 10 for said inlet and outlet passages of the compressor comprises a casing 25 (Fig. 5) which is divided by horizontal partitions to form a gas inlet chamber 26, an air inlet chamber 27 and an outlet chamber 28 for the primary mixture. The valve member 11 is mounted in the casing 25 so as to slide with reference to the partitions forming the chambers, being slotted as shown in Fig. 5 for this purpose. It thus controls simultaneously the passageways through the chambers 26, 27 and 28. Preferably the inner wall of the casing is provided with V-shaped web portions 29 with which the end of the valve member 11 is adapted to coact to gradually open or close said passageways.

The valve member 11 is arranged to be automatically actuated in the operation of the compressor by means of a diaphragm 30 mounted in a laterally extended portion of the casing 25, so as to form in one end thereof a closed chamber 31 which communicates by way of a valve-controlled pipe line 32 with the mixture outlet chamber 28. A rod 33 rigid with the valve member 11 is fixed to the diaphragm 30 and has a bearing in a depending bracket 34 so as to be horizontally slidable in the movements of the diaphragm under the influence of pressure communicated to the diaphragm chamber 31 from the chamber 28. Said diaphragm has connected therewith a variable weight 35

which serves to maintain a predetermined pressure at the outlet of the chamber 28 by its action upon the valve member 11.

Leading from the chamber 28 is the service main 12 having branch pipes 36 which serve to distribute the primary mixture to the burners or unloading devices 13 of suitable or preferred construction.

Preferably some means is employed for proportioning the flow of air and gas to the compressor in the desired ratio. Herein I have shown for this purpose simply a pair of manually operable valves 21 and 22 (Fig. 3).

15 In Fig. 2 I have shown an apparatus employing a positive type compressor. This apparatus comprises a main casing or base 37 providing in its upper portion an annular compressor casing 38 having a rotor 39 therein. An inlet chamber 40 may be formed integral with the base 37 at the inlet side of the compressor casing 38. At the outlet side of the casing 8 there is provided a service or delivery passage 45 discharging 20 into the supply main 46. Within the annular casing 38 is a slide valve 47 in the form of a curved or annular plate which is mounted to float or slide upon the inner peripheral wall 48 of the casing 38 and is provided with an inlet port 49 adapted to establish communication between the compressor inlet and the inlet chamber 40, and an outlet port 50 establishing communication 25 between the compressor outlet and the service passage 45.

30 Eccentrically of the annular casing 38 is mounted a shaft 53 for the rotor 39. The rotor in this instance is provided with a plurality of radially slidable blades 54 maintained by centrifugal force in the operation of the rotor in sliding contact with the inner periphery of the ring valve 47. The port 49 (Fig. 2a) is made of a width somewhat less than the width of the blades 54 so that as the blades pass the port they are maintained against outward movement. Similarly the port 50 is made of less width than the blades.

35 The inlet chamber 40 opens directly into the compressor 38 at the inlet side thereof so as to be controlled by the ring valve 47. Likewise the inlet to the service passage 45 opens directly from the outlet side of the compressor 38 so as to be controlled by the ring valve.

40 The means provided for actuating the ring valve 47 to move the ports 49 and 50 therein into and out of register with the outlet of the inlet chamber 40 and the inlet to the service passage 45 comprises in this instance a pressure-responsive member or diaphragm 55 forming one wall of a closed chamber 56 provided by the base 47, and communicating with the service passage 45 by means of a port 57. A rack bar 58 is

connected with the diaphragm 56 by means of a rod 59, and is connected with a gear segment 60 on the lower outer periphery of the ring valve by suitable means, such as a pinion 61. A suitable bearing bracket 62 is provided for the rod 59, and the rod also has a bearing in one wall of a housing 63 formed in the base immediately below the annular casing 38 and closed therefrom by the ring valve. The housing 63 thus constitutes a chamber for enclosing the gear means, and in practice the housing may be filled with oil. The diaphragm chamber may have a removable end wall 66 to permit of access to the operating mechanism.

For the purpose of insuring the maintenance of a predetermined minimum pressure in the service main, I provide means capable of acting upon the ring valve to position it with the ports 49 and 50 located to permit the passage therethrough of the proper volume of air or other fluid. This means herein comprises a series of weights 67 suspended upon a cord 68 which passes over a pulley 69, and is secured to a block 70 fixed upon the rod 59.

In the event that the rotor 39 should continue to operate after the ring valve 47 has been moved into such position as to completely close the outlet of the compressor, I provide in order to avoid injury to the apparatus, a relief valve 71 in a chamber 72 which is arranged to communicate at all times with the outlet passage 45 through a port 45*. The valve 71 is normally held by a spring 73 in position over a port 74 which is arranged to register with one end of the port 50 when the latter completely closes the outlet passage. The spring is arranged to yield only under an extraordinary pressure, to prevent injury to the apparatus.

While I have shown in the two forms of the invention illustrated, controlling means in which the two valves are integrally connected, it will be understood that this construction is not essential but that any other or preferred form of mechanism for coordinating the operation of the two valves may be employed. Moreover, in some cases it may be convenient or desirable to have the valves controlled by means other than the pressure in the service main, as for example, by electric or magnetic means operating under the control of a thermostat or other automatic device.

When the apparatus is used in a gaseous fuel supply system where two gases, such as air and fuel gas are passed through the compressor, a high degree of efficiency is obtained in the mixing of the gases as well as in the combustion thereof. Thus, the provision of my improved controlling means, coordinating the volume of mixture discharged by the compressor into the service main at any given time with that entering

the compressor, renders it possible to eliminate the return flow through a by-pass of an excess or unused portion of the mixture as in prior apparatus. This is advantageous because the return of a greater or less volume of unused gas has the effect of varying the suction intensity at the compressor inlet, and such variation, owing to the difference in the specific gravities of gas and air, tends to vary the rates of flow of the gases being mixed. Also, the provision of a valve at the inlet to the service line tends to prevent fluctuation in pressure or surging therein, with the result that the pressure in the service line is maintained more nearly constant and hence the velocity of the mixture at the burners is maintained substantially uniform. This is desirable because variations in the velocity at which the gaseous mixture is discharged produces a disproportionate variation in the amount of air entrained for intermixture and combustion.

But whether the apparatus is used as a part of a fuel supply system, or for other purposes where it is desired to supply a varying volume of fluid under pressure, my invention effects a substantial saving in the amount of power consumed in the operation of the compressor, it being evident that the amount of current consumed by the motor varies under differing load conditions. With prior apparatus it is customary to provide a compressor of sufficient capacity to handle the peak load, whereas the normal operative conditions are such that the compressor is called upon to operate normally under much less than peak load capacity. The result is that the compressor is almost constantly performing useless work resulting in a great waste of power and energy. In the case of my apparatus, however, inasmuch as the compressor outlet is controlled with the compressor inlet, a building up of pressure in the service line eliminates in whole or in part the back pressure upon the compressor, so that the compressor is called upon at any given time to handle only that volume which is required to maintain the predetermined pressure in the service line. It will thus be seen that I have produced a means of an advantageous character for supplying a fluid under pressure to maintain in a service line a substantially constant pressure notwithstanding fluctuations in the demand; and while this means is particularly advantageous in a gaseous fuel supply system to maintain the predetermined ratio between the air and gas constituting the primary mixture and in rendering it possible to use in such a system a non-positive or fan type compressor, the apparatus is also capable of advantageous use in supplying a single fluid such as air to a service main because of the substantial saving effected in the power consumed by the compressor while

maintaining the pressure in the service line substantially constant. Indeed, the apparatus is capable of use in a gaseous fuel supply system in which a fuel gas only is admitted to the compressor, the entire supply of air being admitted at the burner outlets. It will therefore be understood that in the interpretation of the appended claims they should not be limited to the mixture of air and gas and it should also be understood that the particular construction and arrangement herein set forth with considerable detail is not considered essential, it being contemplated that various changes may be made by those skilled in the art without departing from the spirit and scope of the invention.

This application is a continuation in part of my copending application Serial No. 430, 574, filed December 13, 1920.

I claim as my invention:

1. An apparatus of the character described comprising, in combination, a compressor having an inlet and an outlet, a service main communicating with the compressor outlet, and valve means for controlling simultaneously and at all times the flow of fluid through said inlet and outlet openings whereby to coordinate the volume discharged from the compressor at any given time with that entering and passing through the compressor. 85

2. A compressor having inlet and outlet ports, valve means adapted to control the respective ports, and means for simultaneously operating said valve means whereby to coordinate the volume discharged from the compressor at any given time with that entering and passing through the compressor. 100

3. A compressor having inlet and outlet ports and a slide valve adapted in the same movement to open or close the respective ports simultaneously. 105

4. A compressor having juxtaposed inlet and outlet ports and a valve member in the form of a single plate adapted to close both ports simultaneously. 110

5. An apparatus of the character described comprising a compressor having an inlet and an outlet, and a unitary means for controlling both the inlet and the outlet whereby to equalize at all times the volume entering, passing through and leaving the compressor, said means being controlled by the pressure at the outlet and adapted when such pressure exceeds a predetermined minimum to close completely said outlet. 115

6. The combination with a service main having a plurality of burner outlets, of a compressor having inlet and outlet ports arranged in juxtaposition, with the outlet port communicating with the service main, and a single valve member for controlling both of said ports and serving to close the outlet port when the pressure in the service main 120

125

130

- exceeds a predetermined minimum whereby to prevent a reversal in the direction of flow of the gaseous fuel in the service main with a fall in the demand. 60
- 5 7. The combination with a service main having outlets, of a means for supplying a gaseous fluid to said main comprising a compressor having an outlet communicating with the service main, and an inlet communicating with a source of supply, and valve means controlled by the pressure in the service main at the compressor outlet adapted to govern the flow of the gaseous fluid to the compressor and also from the 65 compressor to the service main whereby the fractional compressor capacity volumes will be equivalent to the volumes synchronously discharged from the service main at its outlets. 15
- 10 8. The combination with a service main having a plurality of burner outlets, of a compressor having an inlet and an outlet, the latter communicating with the service main, and valve means for controlling the 70 flow of the gaseous fuel to and from the compressor, said means being adapted to maintain the pressure in the service main substantially constant by limiting the volume entering and passing through the 75 compressor at any given time to the volume consumed at said outlets at that time. 20
9. An apparatus for mixing air and gas for combustion comprising a compressor having an inlet and an outlet, said inlet 80 communicating with a source of gas supply and with a source of air supply, and said outlet communicating with a service line, and means controlled by the pressure in the service line at the compressor outlet for 85 simultaneously opening or closing the inlet and outlet ports of the compressor, whereby the volume flowing through the compressor and the volume discharged from the service main are equalized. 40
- 45 10. A compressor having inlet and outlet openings, means providing a pair of passageways communicating with the compressor inlet and a passageway communicating with the compressor outlet, one of said inlet passageways connecting with a source of gas supply and the other one of said inlet passageways connecting with a source of air supply, means for controlling the flow of air and gas through said passageways in a predetermined proportion, and valve means for controlling simultaneously the flow of air and gas to the compressor inlet and of the mixture of air and gas from the compressor outlet whereby to coordinate the 90 volume discharged from the compressor at any given time with that entering and passing through the compressor. 100
11. A compressor comprising a casing, means providing a chamber at one side of the casing divided to form two passageways therethrough, the compressor casing having its inlet communicating with one of said passageways and its outlet communicating with the other one of said passageways, and a valve member in the chamber operable to 105 control both of said passageways. 110
12. A compressor having a casing, means providing a chamber adjacent the casing having a plurality of passageways therethrough, the compressor having an inlet 75 communicating with certain of said passageways and an outlet communicating with the other of said passageways, valve means in said chamber for controlling said passageways, and means for actuating said valve member comprising a closed chamber communicating with the compressor outlet and a diaphragm subject to the pressure in said closed chamber and connected with the 80 valve member. 115
13. A compressor having inlet and outlet openings, the latter being adapted to discharge into a service line whereby to supply fluid under pressure thereto, and automatically operable valve means operable 90 to restrict or enlarge simultaneously and to the same degree the effective areas of said openings. 120
14. A compressor having a casing providing a passageway extending the compressor inlet to a terminal point adjacent the compressor outlet and a single valve member at this point for synchronously controlling the circulation of fluids into and out of the compressor and into a service main. 95 125
15. A rotary compressor having an inlet port and an outlet port juxtaposed, and a casing providing a housing for the juxtaposed ports, and a single valve member in said casing operable to simultaneously control the said ports. 130
16. A compressor having inlet and outlet ports, a valve means mounted in each port, a service main communicating with the compressor outlet, and control means operatively connected with said valve means, said control means being connected in the service main and comprising a constant non-resilient member opposing the pressure in said main. 110 135

In testimony whereof, I have hereunto affixed my signature.

THERON L. HILES.
